Primary Examiner — Michael C Stout*Assistant Examiner* — Melvin L Davis(74) *Attorney, Agent, or Firm* — Kunzler Bean & Adamson; Bruce R. Needham**CLAIM**

The ornamental design for a stand up paddle board with transparent viewing window, as shown.

DESCRIPTION

FIG. 1 is a top view of a stand up paddle board with transparent viewing window;

FIG. 2 is a bottom view thereof; and,

FIG. 3 is a side view thereof.

The broken lines illustrate portions of the stand up paddle board with transparent viewing window that form no part of the claimed design.
